United States Patent Office

Des. 221,538
Patented Aug. 24, 1971

221,538

PERISCOPE-TYPE REAR VIEW MIRROR

Lynn Harold Hodge, Highland Park, Mich.
(12618 Wyoming Ave., Detroit, Mich. 48238)

Filed Apr. 6, 1970, Ser. No. 22,270

Term of patent 3½ years

Int. Cl. D12—14

U.S. Cl. D14—6

FIG.5

FIG.4

FIG.3

FIG.2

FIG.1

FIG. 1 is a side view of a periscope-type rear view mirror in open position.

FIG. 2 is an opposite side view in closed position.

FIG. 3 is a 3/4 front view from above in closed position.

FIG. 4 is a 3/4 front view from above in open position.

FIG. 5 is a 3/4 rear view.

The automobile roof shown in broken lines is included for illustrative purposes only.

I claim:

The ornamental design for a periscope-type rear view mirror, substantially as shown and described.
